CLAIM

The ornamental design for a container, as shown and described.

DESCRIPTION

FIG. 1 shows a perspective view of a container according to my new and ornamental design when closed,

FIG. 2 is a top plan view thereof,

FIG. 3 is a bottom plan view thereof,

FIG. 4 is a front elevational view thereof,

FIG. 5 is a rear elevational view thereof,

FIG. 6 is a left side elevational view thereof,

FIG. 7 is a right side elevational view thereof,

FIG. 8 is a perspective view thereof with the cover lifted and the bottom tray rotated for access to the larger compartment therein,

FIG. 9 is a top plan view of FIG. 8,

FIG. 10 is a left side elevational view of FIG. 8,

FIG. 11 is a right side elevational view of FIG. 8,

FIG. 12 is a bottom plan view of FIG. 8,

FIG. 13 is a rear elevational view of FIG. 8,

FIG. 14 is a front elevational view of FIG. 8,

FIG. 15 is a top plan view thereof with the cover lifted and the bottom tray rotated for access to the smaller compartment therein; and,

FIG. 16 is an exploded view thereof.
